UNITED STATES PATENT OFFICE.

SAMUEL JACKSON SMITH, OF MINEOLA, TEXAS.

COMBINED COUCH AND BATH-TUB.

SPECIFICATION forming part of Letters Patent No. 630,416, dated August 8, 1899.

Application filed February 10, 1899. Serial No. 705,198. (No model.)

To all whom it may concern:

Be it known that I, SAMUEL JACKSON SMITH, a citizen of the United States, residing at Mineola, in the county of Wood and State of Texas, have invented a new and useful Combined Couch and Bath-Tub, of which the following is a specification.

This invention relates to a combined lounge and bath-tub, the object being to provide an ornamental, strong, and serviceable device of the character specified which may be used either as an article of furniture or as a bathing apparatus and which can be readily rolled from place to place for use either in a bedroom or parlor or other apartment of a house.

With these ends in view my invention consists in the novel combination of elements and in the construction and arrangement of parts which will be hereinafter fully described and claimed.

To enable others to understand the invention, I have illustrated the preferred embodiment thereof in the accompanying drawings, forming a part of this specification, and in which—

Figure 1 is a perspective view of a combined lounge and bath-tub constructed in accordance with my invention and with parts broken away to show more clearly certain of the inside construction. Fig. 2 is a plan view of the same, showing the top or lid raised. Fig. 3 is a longitudinal section of the same, showing the top or lid closed. Fig. 4 is a transverse section taken on the line 4 4 and looking in the direction of the arrow, Fig. 3. Fig. 5 is a detail of a portion of the tub and the side and end guards, respectively.

Similar characters refer to like parts in all the figures of the drawings.

The bath-tub, which may be of any suitable construction and which will be herein-after described, is supported within a box-body or framework A, consisting of the two longitudinal side pieces 2 and 3, between which the end pieces 4 and 5 are secured by some suitable fastening means, and the box-body is ordinarily made in rectangular form, as indicated, and the end piece 4 is set back from the outer edges of the side pieces 2 and 3, these parts being usually made of some suitable wood, and the body thus formed is

connected on the under side thereof by a series of cross-bars 6 and by the board 7, the latter constituting the floor or bottom of the heating-chamber, and the cross-bars are separated or spread apart and are disposed a slight distance above the lower edges of the side pieces 2 and 3, the structure thus formed being light and strong, as it is obvious that it is subjected to considerable stress when in use, due to the combined weight of the bather, the water, &c. The tub is designated by B, and it may be of any suitable form, it usually being constructed of zinc, and its upper edge being flush with the upper edges of the side pieces 2 and 3 and end piece 5. The transverse bars 6 are squared at their opposite ends to fit against the inside flat faces of the side pieces 2 and 3, respectively, and they are provided with rectangular tongues or projections 6', fitted in grooves 6'', extending longitudinally of the end pieces. As a means for maintaining the tub in place it can be secured to the side and end pieces by suitable fastening devices located at proper intervals and passing through the tub and the framing or boxing near the upper edges of said parts. As a means for holding the tub more securely in place I prefer to mount the same upon the cross-bars 8, located, respectively, in proximity to the cross-bars 6, the engaging surfaces of which are correspondingly shaped.

In the present case the lower side of the tub which rests against the cross-bars is convex and is also curved, as at 9, and such curved portion 9 fits in the concavities 10, formed in the cross-bars 8, this construction serving to uphold the tub, as well as to prevent lateral movement thereof. It will be seen that the outermost cross-bar 8 is against the end piece 5 of the framing, it being held in such position by a suitable fastening means, and any convenient devices may be employed for maintaining the remaining cross-bars in position between the side pieces 2 and 3 of the framework.

The boxing A incloses at one end thereof the tank C, adapted to contain a supply of water to be heated and in communication with the tub B, the tank being located in the space between the end piece 4 and the head of the tub and the rear wall thereof being inclined,

as at 12, to fit against the correspondingly inclined under portion 13 of the head of the tub, thereby adding to the stability. The tank C is rectangular in cross-section, and to 5 further add to the strength of the device filling-blocks 14 and 15 are provided, these being located in the spaces between the framing and the tank and tub, respectively, and in engagement with said parts, said blocks 10 being beveled along the edges thereof in engagement with the tank and tub, respectively. The end piece 4 has an opening 16, by which access may be readily had to the inside of the heating-chamber, said opening being normally closed by the door 17, hinged to the side piece 3, and having its outer face when 15 shut flush with the end pieces and provided with a knob 18, by which it may be opened.

In order that the article may present a 20 handsome appearance, the boxing or framing A will be furnished with suitable upholstery, which is secured in place in such manner that it can cover all joints.

The water-tank C communicates with the 25 tub through the supply pipe or conduit 19, having a faucet 20, by which the supply of water can be controlled, the inner end of said pipe being located inside the tank. The water-tank C is heated by burners 21 and 22, 30 which may be of any suitable construction, located near the bottom of the tank and carried at the ends of the pipes 23 or 24, which branch oppositely from the main pipe 25, depending from the hydrocarbon-tank 26, which 35 is removably secured in the inside of the boxing, the side piece 3 having a door 27, which can be opened for the purpose of reaching the tank to fill the latter, and said tank and burners will be provided with the usual devices for 40 controlling the supply of the illuminating fluid to the burners, which devices can be reached by opening the door 17. Said door 17 and the door 27 will be normally closed by spring-catches, and the hinges between the 45 same and the framing will be of such a construction as to hide the same to as great an extent as possible when the apparatus is upholstered.

The boxing A will be provided at its 50 corners or other suitable points with casters or rollers, as 28, by which it may be shifted from place to place as the user may wish.

I dispose above the burners 21 and 22 the tubes or pipes 29 and 30 to promote the draft furnished to the flame, and to also divide the water, so that it can be more quickly heated, and said tubes can be secured to the bottom of the tank C to register with the openings 31 and 32 therein.

60 The tub B, at its foot and lower side, is provided with a nozzle or short pipe 33, passing through the end piece 5 and which is closed by the valve 34 when it is desired to collect water in the tub, and when it is necessary to 65 drain the tub this valve can be opened and a flexible tube or pipe, as 35, attached, the opposite end of the tube being passed through

a window or other opening, so that the water can be siphoned without the necessity of moving the apparatus.

The cover or top of the couch is designated by D, and it is upholstered, as at 36, on its outside, having the raised and chambered head portion 37 at one end and being hinged, as at 38, to the side piece 3. When the device is to be used as a lounge, the cover D of course will be closed; but when the same is to be employed as a bathing apparatus said cover will be raised and will be held in the proper position by a cord or chain, as 39, the 75 opposite ends of which are secured, respectively, to said cover and to the tub.

As a means for preventing the passage of moisture and dampness from the tub or water-tank when either or both are filled with 80 water or after they have both been drained I provide a longitudinal guard, as 40, generally of zinc and which is secured to the under side of the cover by suitable fastening devices, one end of said guard or plate being curved, as 85 90 at 41, to fit within the similarly-shaped chamber 42 of the head 37, and said straight portion 43 of the guard is adapted to cover the tub, while the curved portion 41 is adapted to cover and also to receive the upper edge 95 of the water-tank when the cover D is down, so that moisture cannot possibly pass through to the upholstering or clothing 36.

In connection with the tub B, I provide a series of guards, as E, F, and G, the guards 100 E and F being of substantially similar construction and each of them being composed principally of rubber or other non-absorbent material arranged, preferably, at an inclination at the sides and foot of the tub, the edges 105 of said guards being contiguous, so as to provide a continuous structure for the purpose of preventing water that may be splashed from the tub from falling upon the floor of an apartment, the water striking the inclined guards and running down the same into the tub. The guards E and F are stiffened by 110 the frames, as 46, the end members of which are bent, as at 44, at their lower ends, and such bent portions fit in sockets or openings 115 45 in brackets 46, secured to the inside of the tub near its head and foot, such a construction permitting the removal of the side guard E and the end guard F, which when the tub is not in use can be placed in the same. The 120 two guards E and F are beveled at their adjacent ends and one of them overlaps the other, this relation being readily obtained by reason of their flexibility. The side guard G, which is secured between the guard-plate 40 125 and the under side of the cover D in the cut-away portion 47 of said cover, is of flexible material and is made in two plies to receive the weight 48, which holds the same in the proper inclined position when the cover D is up, and this construction permits the folding of said 130 flexible guard when the cover is to be shut.

Changes in the form, proportion, size, and the minor details of construction within the

scope of the appended claims may be resorted to without departing from the spirit or sacrificing any of the advantages of this invention.

5 Having thus described the invention, what I claim is—

1. In an apparatus of the class specified, the combination with a framing, of a tub disposed in said framing, a cover hinged to the framing and both of said parts being upholstered, a series of inclined guards adapted to be placed along the sides and ends of the tub and one or more of said guards having frames provided with deflected portions, socketed brackets adapted to receive said deflected portions, a heating apparatus at one end of the tub, a water-supply tank communicating with said tub, and a metallic guard-plate secured to the under side of the cover and adapted to extend across the tub and the water-tank and curved to receive said tank, substantially as described.

2. In an apparatus of the class specified, the combination with a box-like framing, and with a cover therefor, said parts being upholstered, of a tub, a series of cross-bars between the side pieces of the framing one or more of which are fitted to receive the similarly-shaped tub; a water-tank between the side pieces and having an inclined portion fitting against the inclined head of the tub, filling-blocks between the water-tank and the tub and beveled to engage said parts, draft-tubes in the water-tank in line with openings in said tank, a heating apparatus including burners disposed beneath said openings, a series of guards disposed along the opposite sides and end of the tub, a discharge-pipe for the tub, a supply-pipe leading from the water-tank into the tub and provided with a faucet, a longitudinal guard-plate secured to the under side of the cover and adapted to extend across the tub and the water-tank and curved at one end to fit within the head of the cover and also to receive the water-tank, substantially as described.

3. In an apparatus of the class specified, the combination with a box-like framing and with a cover hinged thereto both of said parts being upholstered, and said cover having a head-piece concaved upon its under side, a metallic guard-plate secured to the under side of the cover and shaped to fit within the concaved portion of the head-piece, a series of cross-bars between the side pieces of the framing having concaved seats to receive the similarly-shaped portion of the tub, a water-supply tank located in the box-like framing, a heating apparatus including a burner located

below said water-supply tank, a draft-tube 60 above the burner and over an opening in the tank, a water-supply pipe leading from the water-tank to the tub, and a valve in said pipe for controlling the flow of the water to the tub, substantially as described. 65

4. In an apparatus of the class specified, the combination with a box-like framing and with a cover hinged thereto, of a tub located in said box-like framing, a series of socketed brackets secured to the inside of the tub, a 70 pair of overlapping guards angularly disposed and including frames terminating in angular portions fitting in said socketed brackets, a flexible guard connected with the under side of the cover and carrying a weight, 75 a water-supply tank communicating with the tub and provided with a valve, and a heating apparatus under said tank including a burner, substantially as described.

5. In an apparatus of the class specified, 80 the combination with a box-like frame secured therein, of an adjustable cover for the frame having a guard connected therewith and adapted to be moved into operative position to project inwardly of the tub when the cover 85 is raised, and additional inclined guards at other portions of the tub projected inwardly thereof and having the adjacent end portion overlapping.

6. An apparatus of the class specified, comprising a box-like frame, a tub secured within the frame, a cover hinged to the frame, a guard fixed to the cover and adapted to extend inwardly over the adjacent edge of the tub when the cover is raised, and additional 95 inclined guards disposed at the edges of the tub and adapted to be detachably connected therewith.

7. In an apparatus of the class specified, the combination with a box-like frame, and 100 a tub located therein, of a cover hinged to the frame, a guard fixed to the cover and adapted to extend inwardly over the adjacent edge of the tub when the cover is raised, upwardly and outwardly inclined frames 105 detachably connected with an opposite side and adjacent end of the tub, and guards supported by the said frames and having the inner edge portions extending inwardly over the adjacent top edge of the tub, and having 110 the end portions overlapping.

In testimony that I claim the foregoing as my own I have hereto affixed my signature in the presence of two witnesses.

SAMUEL JACKSON SMITH.
